UNITED STATES PATENT OFFICE.

DAVID D. GORDON AND WILLIAM LINDSAY, OF CHICAGO, ILLINOIS, ASSIGNORS TO ECONOMY FUSE AND MANUFACTURING COMPANY, OF CHICAGO, ILLINOIS, A CORPORATION OF NEW YORK.

CANDLE-SOCKET MOUNTING.

Application filed June 13, 1925 Serial No. 36833.

The present invention relates to candle socket mountings.

More particularly the present invention relates to clamping means which are useful in connection with electric fixtures known in the trade as candle sockets. As the description proceeds it will be obvious that the invention is of broader application, but for the purpose of description and illustration reference will be had principally to candle sockets. Candle sockets involve the use of sleeves which are intended to simulate candles more or less closely. The sleeves referred to come in different lengths, and it is desirable to have the electric fixtures adjustable, whereby to accommodate the different lengths of sleeve.

An object of the present invention is to provide a candle socket mounting which is cheap to manufacture and which may be readily adjusted by a person having a minimum of mechanical skill.

A further object is to provide a candle socket mounting having a minimum of parts so connected together that there is little if any likelihood that said parts will become misplaced.

A further object is to provide adjustable clamping means readily applicable to candle sockets as now manufactured and which may be operated by persons having a minimum of mechanical skill.

Further objects will appear as the description proceeds.

5 Referring to the drawings—

Figure 1 is a longitudinal sectional view illustrating a candle socket embodying the principles of the present invention;

Figure 2 is a longitudinal sectional view illustrating, more or less in detail, the clamping member forming part of the present invention; and

Figure 3 is a transverse sectional view taken along the plane indicated by the arrows 3—3 of Figure 1.

The numeral 1 indicates a conduit for enclosing electric wires 2—2 which are connected to the electric socket 3. The numeral 4 indicates ratchet mechanism which may be controlled by the pendant member 5 for controlling the circuit of the electric wires within the conduit 1. The socket 2 is illustrated as having the electric bulb 6 mounted therein. The electric socket 3 is mounted at the

upper extremity of the stem 7, which stem 55 is supported by certain clamping mechanism 8, which will be referred to in detail hereinafter, said clamping mechanism 8 being supported on the extremity of the conduit 1. Surrounding the socket 3, the ratchet mechanism 4, the stem 7 and the clamping mechanism 8 is the sleeve 9, which is carried by the cup-shaped member 10. Said cup-shaped member 10, known as a candle socket, is provided with the boss 11, which may be 65 secured to the conduit 1 by means of the setscrew 12. The bottom portion of the candle socket 10 may be provided with the aperture 13, through which extends the pendant member 5. 70

The clamping mechanism 8 is embodied, preferably, in a rolled metal stamping, bent intermediate of its ends to provide a more or less sleeve-like structure. Said clamping mechanism 8 is provided with the inwardly 75 turned wall 14, which may be interiorly screw-threaded for engagement with the screw-threaded extremity of the conduit 1. Said clamping mechanism is split longitudinally, and has the two clamping jaws 15—15, 80 adapted to receive the stem 7. One of said jaws 15 is provided with the tenon or tongue 16 adapted to fit into a corresponding recess in the opposed jaw 15. Said jaws 15—15 are dove-tailed together by means of said tongue 16, and for this purpose the outer extremity 85 of said tongue 16 should preferably be of a greater dimension longitudinally of the clamping mechanism 8 than is that portion of the tongue 16 which is adjacent to its corresponding jaw 15. It will be understood, 90 of course, that any other preferred type of joint may be used. The opposite sides of the jaws 15—15 are provided with the outstanding ears 17—17. One of said ears is screw-threaded for the reception of the screw 95 18. The other of said ears may have an aperture 19 of slightly greater diameter than the screw 18. One end of the screw 18 is provided with the screw head 20; the other end of the screw 18 is upset, as indicated by the 100 numeral 21, whereby to prevent loss of said screw 18.

In assembling the above described embodiment of the present invention it will be clear that, assuming the sleeve 9 to be removed, 105 the clamping mechanism 8 will be screwed down upon the conduit 1 and the socket 3 may

be mounted in place with the stem 7 lying between the jaws 15-15 of the clamping mechanism 8. The tongue 16 is located within its corresponding recess in the opposite jaw 15, and with the screw 18 located within the ears 17-17, said tongue 16 will be held securely against displacement from its corresponding recess. Vertical and rotary adjustment of the stem 7 and socket 3 may very readily be had when the screw 18 is turned back, and said stem may be securely clamped when the screw 18 is turned up, as shown in Figure 3, whereby to pull the jaws 15-15 into tight clamping engagement with said stem 7. By reason of the upset end 21 of the screw 18, there is little if any likelihood of losing the screw 18.

The pendant member 5 will be disposed in a position to extend through the aperture 13, the ornamental ball at the end of said pendant member being mounted in position, preferably, after said pendant member is positioned within said aperture 13. The sleeve 9 may then be inserted within the cup-shaped member 10.

The present invention provides a device which is cheap to manufacture and which requires no skill in adjusting. Though a preferred embodiment has been described in detail, it will be clear that many modifications will occur to those skilled in the art. It is intended to cover all such modifications that fall within the scope of the appended claims.

35 What is claimed is—

1. In lamp socket mechanism, a conduit for electric wires, elongated clamping holding means mounted on said conduit, an electric socket, a cylindrical stem for supporting said socket and adapted to be located between said holding means whereby to be both rotatably and axially adjustable between said holding means, said holding means having portions jointed together, and screw means disposed on the opposite side of said stem from said jointed portions for holding said holding means in gripping relationship with said stem.

2. In a candle socket, in combination, a candle cup, a candle sleeve, an electric socket within said sleeve, mechanism including a pendant member for controlling said socket, means including a stem for supporting said socket and said mechanism, said candle cup being provided with a hole for permitting the passage therethrough of said pendant member, and means for holding said socket in adjusted position both rotatably and longitudinally, said holding means including a split sleeve-like clamping member having portions jointed together about an axis parallel with the axis of said socket for clamping said stem and having screw means for holding said holding means in gripping relationship with said stem.

Signed at Chicago, Illinois this 9th day of June, 1925.

DAVID D. GORDON.
WILLIAM LINDSAY.
